Primary Examiner — Lauren D Mcvey*Assistant Examiner* — Elisa Maria Pujals(74) *Attorney, Agent, or Firm* — Minder Law Group; Willy H. Wong(57) **CLAIM**

The ornamental design for a shark toy, as shown and described.

DESCRIPTION

FIG. 1 is a front view of a shark toy showing the new design. FIG. 2 is a rear view thereof.

FIG. 3 is a left side view thereof.

FIG. 4 is a right side view thereof.

FIG. 5 is a top view thereof; and,

FIG. 6 is a bottom view thereof.

The evenly spaced broken lines that are immediately adjacent to the claimed areas, and contain additional broken line subject matter, depict the bounds of the claimed design, while all other broken lines depict portions of the article that form no part of the claimed design.

1 Claim, 6 Drawing Sheets(56)
